United States Patent Office

Des. 193,598
Patented Sept. 11, 1962

193,598

HANGER

Malba Maxine Raver, 304 Oak Crest Drive, Parkville, Mo.

Filed Apr. 16, 1962, Ser. No. 69,732

Term of patent 14 years

(Cl. D80—8)

FIG. 1 is an elevational view of a hanger, showing my new design.

FIG. 2 is a view of one end thereof; and

FIG. 3 is a view of the opposite end thereof.

I claim:

The ornamental design for a hanger, as shown.
